UNITED STATES PATENT OFFICE.

JOHN E. COTTON, OF FAIRFIELD, MAINE.

LAWN-SETTEE.

SPECIFICATION forming part of Letters Patent No. 233,732, dated October 26, 1880.

Application filed November 20, 1879.

To all whom it may concern:

Be it known that I, JOHN E. COTTON, of 5
Fairfield, in the county of Somerset and State
of Maine, have invented a new and useful Im-
provement in Lawn-Settees, of which the fol-
lowing is as true and clear a specification as I
am able to make.

Figure 1 is a perspective view of the present
device, parts of the seat being broken away to
10 show some of the details of the construction
of the settee. Fig. 2 is a rear elevation of the
same device; Fig. 3, side elevation, showing
the settee folded.

This device belongs to that class of settees
15 which are designed to fold up for convenience
in moving or packing; and the novelty con-
sists in the peculiar details of the construction
and combination of the several parts, whereby
simplicity in structure, cheapness, strength,
20 and durability are in a very large degree ob-
tained, all as will now be more fully set out
and explained.

In the accompanying drawings, A denotes
25 the back of the settee, which is jointed on each
side, at c', to the rear upper end of the cross-
leg C. These cross-legs C C' are jointed to-
gether near their middle at c, and there is one
pair of these on each side of the settee.

To the upper front ends of the cross-legs C'
30 are jointed, at c'', the front ends of the side bar,
b, of the seat B, so that the seat may be turned
up on the joint c'', as now indicated in dotted
lines in Fig. 1, when it is desired to fold up the
settee.

The seat B is preferably made of slats fixed
35 at their ends on these side bars, b, and so as
to be a little dishing in the shape from front
to rear. The rear free ends of the side bars, b,
rest, when the settee is in use, on the horizon-
40 tal bar a', which extends from side to side of
the back A.

On each side, in the upper face of cross-leg
C', near its foot, as at x, is a notch, into which
the sloping lower ends or feet of the vertical
side bars of the back A can be engaged, so as 45
to lock the back and legs and give firmness
to all the parts.

The back may also, if desired, have cross-
bars from side to side to strengthen it, or for
beauty of finish; likewise rods from side to 50
side, to connect the cross-bars on the two ends.

To fold the settee, it is only necessary to
take hold of the rear edge of the seat and
swing it into a vertical position, when an up-
ward pressure on the rear top ends of the cross- 55
bars C will serve to throw the feet of the side
pieces of the back out of their sockets at x on
C', and then, the cross-legs being folded on
each other, the back A will come flat against
the under side of the seat B. In this shape 60
the settee can be easily carried about or packed
for transportation.

Having thus described my invention, what
I consider new, and desire to secure by Letters
Patent, is—

The folding settee herein described, consist-
ing of the back A, pivoted to the cross-legs C
at their rear upper ends, and seat B, pivoted
through its side bars, b, at the front to the
upper ends of cross-legs C', the rear ends of 70
bars b being free and adapted to rest on the
bar a' of the back when the settee is in use,
the several parts to be locked together in po-
sition by the sloping feet of the side bars of
the back engaging in the notches x of the 75
cross-legs C', substantially as and for the pur-
poses set forth.

JOHN E. COTTON.
